(57) **CLAIM**

The ornamental design for a portable light, as shown and described.

DESCRIPTION

FIG. 1 is a perspective view of a portable light wherein a positionable light source and a positionable accessory (shown in broken line) are shown in a first configuration; FIG. 2 is a second perspective view thereof, wherein the positionable light source and the accessory are shown in a second configuration;

FIG. 3 is a view of a first side of the portable light wherein the positionable light source and the accessory are shown in a third configuration;

FIG. 4 is a view of a second side thereof;

FIG. 5 is a view of a third side thereof;

FIG. 6 is a view of a fourth side thereof with the positionable accessory in the first configuration;

FIG. 7 is a view of a first end thereof with the positionable accessory in the second configuration;

FIG. 8 is a view of a second end thereof; and,

FIG. 9 is the perspective view of FIG. 1 with the positionable accessory in its second configuration.

Broken lines in the DRAWING indicate parts of the portable light that are not claimed and so form no part of the claimed design. The part of the portable light between the break lines is not claimed and so forms no part of the claimed design.

1 Claim, 6 Drawing Sheets
